SAFETY LIMIT-STOP.

1,113,337.

Specification of Letters Patent.

Patented Oct. 13, 1914.

Application filed January 10, 1913. Serial No. 741,227.

To all whom it may concern:

Be it known that I, LESTER C. HART, a citizen of the United States, residing at Youngstown, in the county of Mahoning and State of Ohio, have invented new and useful Improvements in Safety Limit-Stops, of which the following is a specification.

My invention relates to the control of electric motors, and particularly to the control 10 of motors driving a machine or mechanism which has a repeated cycle of operations or travels through limited distances.

My invention can be used for the control of an elevator motor, or a motor driving 15 a hoisting mechanism on an electric crane wherein it is desired to provide a safety limit stop to stop the motor when the elevator car or hoisting device has reached a certain limit of travel. Motors driving 20 hoisting mechanism are usually provided with suitable controllers for starting, stopping and reversing the motor, at the direction of the operator.

One of the objects of my invention is to 25 provide a safety device which will automatically stop the motor and driving mechanism when the mechanism has reached a certain limit of travel regardless of the position or condition of the operator's controller. The 30 device can also be used as an emergency device to stop the motor at any time if the operator's controller fails to work.

Another object is to provide means for reversing the motor from the operator's controller after it has been stopped by the safety device, in order to restore the motor 35 to the normal control of the operator's controller and put the safety device into position for another operation. This is brought about preferably by the operator moving his controller to the usual position 40 for reversing the motor.

Other objects will be obvious from the following description and claims.

45 In working out my invention, I provide a switching device, preferably operated mechanically by movement of the hoisting mechanism when it has reached a certain limit of its travel, which cuts the motor off 50 from the source of supply through the operator's controller and connects the motor so that it acts as a separately excited generator, the armature being shunted by a low resistance which causes the motor to come 55 quickly to rest. The usual hoisting motor is

a series wound motor and to provide a separately excited field, I supply current to the series field winding through a circuit independent of the operator's controller, this circuit containing a resistance which limits 60 the current through the series field to approximately normal full load current. The shunt around the motor armature is also through a circuit which is independent of the operator's controller, so that it makes 65 no difference whether the operator moves his controller or not, when the limit of travel is reached the safety device makes the proper connections for stopping the motor quickly and without undue current 70 values in the motor winding.

Referring to the accompanying drawing, Figure 1 is a diagrammatic view illustrating the principles of my invention, and Fig. 2 is a fragmentary view showing 75 the application of my invention to a hoisting mechanism.

On the drawing, A represents the armature of an electric motor, and F, the field winding thereof.

80 C is a rheostatic and reversing controller having brushes c^1 and c^2 arranged to engage the contacts c^3 , c^4 , c^5 , and c^6 in the manner presently to be described.

R and R^3 are resistances having sections 85 thereof connected to the corresponding sections of the contacts c^3 and c^5 in a well-known and clearly illustrated manner.

c^7 is the controller handle by which the brushes are made to move into engagement 90 with the contacts.

E represents a switching mechanism of the drum controller type showing in development the fixed fingers e^1 , e^2 , e^3 , e^4 , e^5 and the movable contacts g^1 , g^2 , g^3 , g^4 , g^5 , corresponding, respectively, to the fingers, the contacts being connected together.

B is a brake-winding in the wire 1 which connects one terminal of the field winding F to the central section of the contact c^5 , 100 the remaining terminal of the field-winding being connected to the negative supply wire 2. One terminal of the armature A is connected by the wire 3 to the contact c^4 and the other, by the wire 4 to the finger e^4 . The positive supply wire 5 is connected to the central section of the contact c^3 , the branch wire 6 connecting the supply wire to the finger e^5 . The wire 7 connects the contact c^6 and the finger e^1 . The wire 8 is in series with the 110

resistance R' and connects the finger e^2 to the point p on the wire 1 between the field winding F and the brake-winding B. The wire 9 is in series with the resistance R^2 and 5 connects the finger e^2 with the wire 3.

The contacts g' to g^5 are supposed to be rotated by the shaft s , to which the pulley s' is secured. The cable d runs over the pulley and has the weight W' suspended on one 10 end thereof, and the heavier weight w^2 suspended on the other end.

H is a hoisting-drum rotated by any suitable power, as the armature A, and carrying the hoisting-cable h , which passes around 15 the sheave h' in the hoisting-block h^2 , provided with the hoisting-hook h^3 and the arm h^4 , which stands vertically below the weight w^2 , so that when the block h^2 reaches a certain height, the arm will engage and lift 20 the weight w^2 , thereby enabling the weight w' to rotate the shaft s in one direction. When the arm h^4 next descends, the weight w^2 causes the shaft s to rotate in the opposite direction.

25 To hoist a load supported by the hook h^3 , the handle c^7 is moved to the right, causing the brush c' to connect the first section of the contact c^3 and the contact c^4 , and the brush c^2 to connect the first section of the contact c^5 and the contact c^6 . The current flows from the positive wire 5 through the contact c^3 , the brush c' , the contact c^4 , the wire 3, the armature A, the wire 4, the finger e^4 , the contacts g^4 and g' , the finger e' , the wire 7, the contact c^6 , the brush c^2 , the contact c^5 , the wire 1 and the brake-coil B, and the field-winding F to the negative supply wire 2. The current described flows in series through the half of the resistances R 30 and R^3 , the brake-coil B, the armature A, and the field-winding F, thus causing the brake-coil to release the brake, and the motor to hoist the load at its slowest speed. The hoisting speed may be increased by moving 35 the handle c^7 step by step to the right, thereby gradually cutting out the resistances R and R^3 until the upper member of the brush c^4 engages the central section of the contact c^3 and the lower member of the brush c^2 40 engages the central portion of the contact c^5 , when the motor will hoist the load at its greatest speed. When the arm h^4 engages the weight w^2 and lifts the same until the weight w' rotates the controller drum E 45 from the position shown in Fig. 1 to a position at which the contact g' passes beyond the finger e' , and the fingers e^2 , e^3 , e^5 engage the respective contacts g^2 , g^3 , g^5 . In this position of the controller E, the circuit of 50 the brake-winding B is broken at the finger e' , thereby causing the brake to set in a well-known manner. At the same time, the positive terminal of the field-winding F is connected to the positive supply wire 5 by 55 means of the wire 6, the finger e^5 , the con-

tacts g^5 and g^3 , the finger e^3 , and the wire 8 which has the resistance R' in series therewith, the field-winding being thereby connected across the supply wires 2 and 5 and in series with the resistance R' , this circuit 60 being independent of the operator's controller C. Also, the armature A is connected in a dynamic braking circuit, as follows: from one terminal of the armature A through the wire 3, the resistance R^2 and the wire 9, the finger e^2 , the contacts g^2 and g^4 , the finger e^4 , and the wire 4 to the remaining terminal of the armature. This 65 dynamic braking circuit will quickly bring the load to rest which will be prevented from descending by the release of the brake controlled by the winding B.

If it be desired to lower the load, the handle c^7 is moved to the left so that the brush c' connects the contact c^4 and the first section of the contact c^5 , and the brush c^2 connects the first section of the contact c^3 to the contact c^6 . The motor circuit is then as follows: from the positive supply wire 5 through the wire 6, the finger e^5 , the contacts g^5 and g^4 , the finger e^4 , the wire 4, the armature A in a direction opposite to its former direction, the wire 3, the contact c^4 , the brush c' , the contact c^5 , the wire 1 and the brake-winding B, and the field winding F to the negative supply wire 2. The current in this circuit obviously causes the brake controlled by the winding B to be released and the motor armature to rotate in the opposite direction, thereby causing the load to be lowered. The armature remains connected in a closed circuit with the resistance R^2 . The rotation of the armature in lowering causes the arm h^4 to descend, permitting the weight w^2 to rotate the controller E back to its former position, shown 100 in Fig. 1. The contacts g^3 , g^4 , first leave the fingers e^3 , e^4 , thereby opening the said closed circuit around the armature. Immediately thereafter the contact g' engages the finger e' and the contact g^5 leaves the finger e^5 . The circuit is now as follows: from the positive supply wire 5 through the right-hand half of the resistance R , the right-hand section of the contact c^3 , the brush c^2 , the contact c^6 , the wire 7, the finger e' , the contacts g^4 , g^5 , the finger e^4 , the wire 4, the armature A, the wire 3, the contact c^4 , the brush c' , the first section of the contact c^5 , the left-hand half of the resistance R^3 , the wire 1 and the brake-winding B, and the field-winding F to the negative supply wire 2. The current in this circuit flows in series 110 through the field, the armature, and the resistance R , the direction of the current through the armature being unchanged. The load may now be lowered under the rheostatic control of the operator's controller C in an obvious manner. To stop the motor the handle c^7 is moved to the position 115 120 125 130

shown, whereupon the motor and brake circuits are opened, thereby permitting the brake-winding to release the brake.

I claim—

- 5 1. In a motor control system, a motor, a controller for the motor, and a switching device for stopping the motor comprising a means for opening the motor circuit between the motor and the controller, means for closing a circuit from the source through the motor field winding, and means for closing a local circuit through the motor armature exclusive of the controller.
- 10 2. In a motor control system, a motor, a controller for the motor, and a switching device operated by the motor and comprising means for separately exciting the motor field, and means for shunting the motor armature through a circuit independent of the controller.
- 15 3. In a motor control system, a motor having a series field winding, a controller for the motor, a switching device for separately exciting the series field through a circuit independent of the controller, and connecting the motor armature in a closed circuit, and means operated by the motor for operating the switching device.
- 20 4. In a motor control system, a motor, a brake-winding, a controller for the motor, and a switching device for stopping the mo-

tor comprising a means for deenergizing the brake-winding, means for closing a circuit from the source through the motor field winding independent of the controller, and means for closing a local circuit through the motor armature.

5. In a motor control system, a motor, a reversing controller therefor and a device operated by the motor and comprising means for opening the motor circuit through the controller, means for closing a shunt around the armature, and means for closing a circuit through the motor field and independent of the controller and for including the armature in the motor circuit when the controller is reversed.

6. In a motor control system, a motor, controller contacts for connecting the motor armature and field in series to a source of supply, and a switching device operated by the motor for connecting the motor field to a source of supply exclusive of the controller contacts and connecting the motor armature in a closed circuit exclusive of the controller contacts.

Signed at Pittsburgh, Pa., this 8th day of January, 1913.
